(57) **CLAIM**

The ornamental design for the multi-functional table for camping chair, as shown and described.

DESCRIPTION

FIG. 1 is a top plan view of a multi-functional table for a camping chair showing my new design without the retainer piece inserted.

FIG. 2 is a front and bottom perspective view thereof.

FIG. 3 is an enlarged rear and bottom perspective view of the mounting portion.

FIG. 4 is a rear perspective view of the multi-functional table with the mounting portion rotated from the vertical position.

FIG. 5 is a front perspective view of this design.

FIG. 6 is a bottom perspective view showing the tray portion of this device rotated 90 degrees relative to the mounting portion.

FIG. 7 is a top perspective view of the tray portion with the retainer piece inserted therein.

FIG. 8 is a top plan view of the mounting portion of the multi-functional table for camping chair as shown in FIG. 1 with the chair lock in an unsecured position, shown separately to depict aspects of the design that may not be apparent from the other views presented herein.

FIG. 9 is a bottom plan view of the mounting portion shown in FIG. 8 with the chair lock in a secured position.

FIG. 10 is a front perspective view of the multi-functional table of this design in a position of use, secured onto a camping chair, and with the retainer piece shown separated from the table portion; and,

FIG. 11 is a close-up in use view showing an unclaimed pad or book disposed upon the slightly downward canted table portion, angled toward a would be sitter for easy reading, wherein the book or pad is held from falling off the tray by the retainer, and further showing the mounting portion secured to a leg of a camping chair.

Any broken or dashed lines set forth in the drawing figures depict environment subject matter and form no part of the claimed design.
